UNITED STATES PATENT OFFICE.

CHARLES KELLY, OF PASSAIC, NEW JERSEY, ASSIGNOR TO THE READ HOLLIDAY & SONS, LIMITED, OF NEW YORK, N. Y.

ACETYLENE-GAS GENERATOR.

SPECIFICATION forming part of Letters Patent No. 608,869, dated August 9, 1898.

Application filed February 15, 1898. Serial No. 670,416. (No model.)

To all whom it may concern:

Be it known that I, CHARLES KELLY, of Passaic, in the county of Passaic and State of New Jersey, have invented certain new and 5 useful Improvements in Acetylene-Gas Generators, of which the following is a full, clear, and exact description.

The object of the invention is to provide certain new and useful improvements in acetylene-gas generators whereby the hydrate of lime is removed automatically from the generator to keep the flow of the water from the tank to the generator unobstructed, and in case of any abnormal pressure of gas the latter is vented to the open air before the water seal in the tank is broken.

The invention consists of novel features and parts and combinations of the same, as will be described hereinafter, and then pointed out in the claims.

Reference is to be had to the accompanying drawings, forming a part of this specification, in which similar characters of reference indicate corresponding parts in all the figures.

Figure 1 is a side elevation of the improvement, with parts in section. Fig. 2 is a plan view of the same, and Fig. 3 is an enlarged transverse section of part of the generator on the line 3 3 in Fig. 1.

The improved acetylene-gas generator is provided with a holder A and a diaphragm B for dividing the holder into an upper compartment C and a lower compartment D. In the diaphragm B is arranged a downwardly-extending pipe E, terminating at its lower end a short distance from the bottom of the lower compartment D, so that water can pass through said pipe E up into the compartment C in case of abnormal pressure.

From the water-compartment D lead one or more main pipes F to a chamber G', arranged on a gas-generator G, each pipe F being provided with a valve F' for controlling the flow of the water from the compartment D into the chamber G', connected with the interior of the generator, so that the water can rise in the generator to the calcium carbid contained in the basket H, held in the generator. The gas generated by the contact of the water with the calcium carbid passes from the upper portion of the generator through a

pipe I, having a valve I', and continuing in a coil I², arranged in the upper portion of the compartment C, the upper end of the coil I² extending, as at I¹, through the top of the holder A to a governor J, of any approved construction, for controlling the amount of gas passing to the service-pipe K.

The bottom G² of the generator G is inclined downwardly to the chamber G' and opens into the latter at the lower end of said bottom, so that water can pass from the chamber into the lower portion of the generator, said chamber also opening into a settling-chamber G³, formed below the bottom G² in the extreme lower portion of the generator. Now it is evident that the hydrate of lime—that is, the residue left by the process of generating the gas by the water contacting with the calcium carbid—drops down on the bottom G² and slides from the same in a downward direction into the chamber G' and from the latter to the settling-chamber G³, in which it accumulates.

The top of the generator G is normally closed by a removable cover G⁴, held on a screw-rod G⁵, screwing in a yoke G⁶, pivoted at G⁷ to the outside of the generator and provided with an arm G⁸, connected by a link L' with an arm L², secured to the stem L³ of an outlet-valve L, leading from the lower hopper-bottomed end of the settling-chamber G³.

When the calcium carbid in the basket H has been used up and it is desired to replace the same, then the valve F' is closed to shut off the water from the compartment D. The operator now screws the screw-rod G⁵ upward to lift the cover G⁴ off its seat, and then the yoke G⁶ is swung over to the position indicated in dotted lines at the left in Fig. 1, so that the arm G⁸ swings upward and moves the link L' and the arm L² in a like direction to open the valve L, so that the residue accumulated in the settling-chamber G³ passes through the valve L to the outside, together with the water in the generator. The basket H is now removed and refilled with calcium carbid and then replaced in the generator, after which the yoke G⁶ is swung back to its normal position to bring the cover G⁴ over the top of the generator. Now by screwing

the screw-rod G^5 downward the cover is carried in a like direction and is finally seated on its seat on the top of the generator to securely close the latter.

5 By the arrangement described the hydrate of lime is discharged automatically from the generator proper into a suitable chamber and allowed to flow out of the latter upon automatically opening the valve L on removing 10 the cover G^4 , as above explained.

By the arrangement described the flow of the water from the compartment D through the pipe F into the chamber G' is not interrupted by the hydrate of lime, as the latter 15 settles into the chamber G^3 and leaves the passage for the water to the generator open.

An air-vent pipe N extends into the water-compartment D , the lower end of said pipe being a short distance above the lower end 20 of the diaphragm-pipe E , so that in case excessive pressure of the gas generated drives the water back through the pipe F into the compartment D and from the latter up the pipe E into the upper compartment C then 25 the lower end of the pipe N is uncovered before the lower end of the pipe E is reached, so that the gas or air can readily pass up through the pipe N to the outer air before the water seal at the lower end of the water- 30 pipe E is broken.

The pipe N is provided within the compartment C with a water-relief or branch pipe N' , so that any water forced up the pipe N can readily drain back through the pipe N' into the compartment C to leave the pipe N unobstructed for the ready passage of the 35 air or gas through the pipe, as above described. The upper ends of the generators G are also provided with relief-pipes O , having check-valves O' .

It is understood that by the arrangement described the gas generated in the generator first passes up through the non-decomposed carbid, which dries the gas, and then the 45 latter passes through the coil I^2 , which cools the gas previous to its passage to the service-pipe K . The amount of gas made is exactly in proportion to the consumption, as it is evident that if more gas is made than consumed 50 the surplus gas will drive the water in the generator downward from the carbid and through the pipe F back into the compartment D , as previously mentioned. The cover G^4 of each of the generators G can now 55 be removed by automatically opening the outlet-valve L , so that the generator is drained of any water which may have been carelessly left in it, and at the same time the hydrate of lime is discharged from the settling-chamber.

60 Having thus fully described my invention, I claim as new and desire to secure by Letters Patent—

1. An acetylene-gas apparatus, provided with a generator for containing the calcium carbid and having an inclined bottom, a settling-chamber below the said generator, and a water-inlet chamber connected with a water-

supply and opening into the said generator directly above the inclined bottom thereof and into the said settling-chamber, substantially 70 as shown and described.

2. In an acetylene-gas apparatus, a generator having a bottom inclined to one side, a settling-chamber below the inclined bottom of the generator, and a water-chamber arranged at one side of the generating and settling chambers and having its outer wall inclined downwardly, said water-chamber being connected with a water-supply and opening into the generating-chamber directly above 80 the inclined bottom thereof and into the settling-chamber, substantially as and for the purpose set forth.

3. An acetylene-gas apparatus, provided with a generator for containing the calcium carbid and having an inclined bottom, a settling-chamber for the hydrate of lime and into which discharges said inclined bottom, an outlet-valve for the said settling-chamber, a removable cover for the said generator, and means for connecting the said cover with the said outlet-valve, to automatically open the latter upon opening the said cover to drain the water from the generator, substantially 90 as shown and described.

4. An acetylene-gas apparatus, provided with a generator for containing the calcium carbid, an outlet-valve for the hydrate of lime, and a cover for closing the generator and connected with the said outlet-valve for 100 opening the latter automatically upon removing the said cover, substantially as shown and described.

5. An acetylene-gas apparatus, provided with a generator for containing the calcium carbid, an outlet-valve for the hydrate of lime, a cover for closing the generator, and mounted on a pivoted yoke, and a connection between the said yoke and the said outlet for 105 opening the latter automatically upon swinging the yoke over and removing the cover from the generator, substantially as shown and described.

6. An acetylene-gas apparatus, provided with a generator adapted to receive the calcium carbid, a cover for the said generator, a screw-rod carrying the said cover, a pivoted yoke in which screws the said screw-rod, an outlet-valve for the hydrate of lime for the said generator, and a connection between the 115 said yoke and the said valve for opening the latter upon swinging the yoke over and removing the cover, and for closing the valve upon closing the generator with the cover, substantially as shown and described.

7. In an acetylene-gas apparatus, a generator having an inclined bottom, a settling-chamber below the generator and receiving the hydrate of lime therefrom, an outlet-valve in the bottom of the settling-chamber and 130 having an arm on its stem, a pivoted yoke at the top of the generator, and provided with an arm at one side, a screw carried by the yoke, a cover carried by the screw, and a link

connecting the said arms, substantially as herein shown and described.

8. An acetylene-gas apparatus, provided with a water-tank having a diaphragm for forming two compartments in the tank, a water-pipe extending from the diaphragm downward into the lower compartment, a vent-pipe extending into the lower compartment, the lower end of said pipe being above the lower end of said diaphragm-pipe, and a

water-relief pipe leading from the said vent-pipe into the upper compartment, for discharging water contained in the vent-pipe back into the tank to free the vent-pipe for the passage of air or gas, substantially as 15 shown and described.
